UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR-CASE BODY.

SPECIFICATION forming part of Design No. 18,878, dated January 22, 1889.

Application filed December 28, 1888. Serial No. 294,876. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor-Case Body, of which the following is a specification, reference being 10 had to the accompanying drawing, forming part thereof.

Said drawing represents in front elevation a photograph-exhibitor-case body embodying our design, the lid or cover being absent or 15 understood to be thrown back out of sight.

The leading feature of our design consists in the substantially half-oval-shaped photograph-exhibitor-case body having upon one of its sides a substantially half-oval-shaped 20 centrally-arranged figure and a curved bead arranged between the said figure and the curved edge portion of the said side, whereon such centrally-arranged figure is arranged, the outline of the centrally-arranged substantially half-oval-shaped figure being in correspondence and harmony with the substantially half-oval shape of the case-body, while the bead or rib corresponds with the curved 25 outline portions of the said centrally-arranged figure and the side of the case-body whereon the two are arranged.

In said drawing, A indicates the substantially half-oval or half-elliptic shaped photograph-exhibitor-case body, having upon one of 30 its sides a centrally-arranged substantially half-oval-shaped figure, B, and a curved rib or bead, C, which latter is arranged intermediate of the said figure B and the curved edge

a' of said side a of the case-body. The centrally-arranged figure B is preferably raised 40 from the plane of the side a of the case-body, although if flush with said side or somewhat depressed therein the general effect would to a certain extent be produced, since in each instance it would in outline harmonize with 45 the substantially half-oval shape of the case-body. The rib or bead C is concentric with the curved edge a' of the side a, whereby it harmonizes with the curvature involved in the substantially half-oval shape of the case- 50 body, and also harmonizes with the curved portion of the edge, border, or outline of the centrally-arranged figure B. The substantially half-oval side a herein shown may be considered as the front side of the case-body, 55 it being deemed unnecessary to show the corresponding substantially half-oval-shaped rear side, which latter can of course be ornamented like the front side or be plain or otherwise, as desired. 60

What we claim is—

The design for a photograph-exhibitor-case body, consisting of the substantially half-oval-shaped body, and having upon its side a a rib or bead, C, curved in correspondence with the 65 curved edge portion of said side, and a centrally-arranged substantially half-oval-shaped figure, B, corresponding in outline with the general outline of the said side a, whereon it is arranged, substantially as shown and described. 70

GEORGE M. PORTEOUS.
FREDERICK S. MILLER.
